United States Patent

Des. 238,684
Patented Feb. 3, 1976

238,684

CONFERENCE MICROPHONE OR SIMILAR ARTICLE

David K. Walz, Atlanta, Ga., assignor to Lanier
Electronic Laboratory, Inc., Atlanta, Ga.

Filed Feb. 14, 1974, Ser. No. 442,658

Term of patent 14 years

Int. Cl. D14—01, 03
U.S. Cl. D26—14 J

FIG 1

FIG 2

FIG 3

FIG 4

FIG 5

FIG 6

FIG 7

FIG. 1 is a perspective view of a conference microphone embodying the design of the present invention;

FIG. 2 is a front elevation view of the conference microphone;

FIG. 3 is a right side elevation view thereof;

FIG. 4 is a left side elevation view thereof on a reduced scale;

FIG. 5 is a rear elevation view thereof;

FIG. 6 is a top plan view thereof; and

FIG. 7 is a bottom plan view thereof.

I claim:

The ornamental design for a conference microphone or similar article, substantially as shown.
